UNITED STATES PATENT OFFICE.

FREDERIC A. MORLEY, OF BROOKLYN, NEW YORK, ASSIGNOR OF ONE-HALF TO CLARENCE A. PHELAN, OF BROOKLYN, NEW YORK.

NON-REFILLABLE BOTTLE.

SPECIFICATION forming part of Letters Patent No. 723,004, dated March 17, 1903.

Application filed July 17, 1901. Renewed July 31, 1902. Serial No. 117,747. (No model.)

To all whom it may concern:

Be it known that I, FREDERIC A. MORLEY, a citizen of the United States, and a resident of Brooklyn, in the county of Kings and State 5 of New York, have invented certain new and useful Improvements in Non-Refillable Bottles, of which the following is a specification.

The invention relates to improvements in non-refillable bottles; and it consists in the 10 novel features, structure, and combinations of parts hereinafter described, and particularly pointed out in the claims.

The object of the invention is to produce a bottle having within its neck means for preventing the refilling of the bottle and which bottle, while containing the means for preventing refilling, will permit of the proper flow of the liquid therefrom.

The invention will be fully understood from 20 the detailed description hereinafter presented, reference being had to the accompanying drawings, in which—

Figure 1 is a central vertical section through a portion of a bottle constructed in accordance with and equipped with attachments embodying my invention. Fig. 2 is a like view 25 of same, the attachments being illustrated in side elevation instead of, as in Fig. 1, in section. Fig. 3 is a horizontal section through 30 the neck of the bottle on the dotted line 3 3 of Fig. 1. Fig. 4 is a horizontal section through the bottle on the dotted line 4 4 of Fig. 1. Fig. 5 is a detached side elevation, partly in section, of a plug embracing a modification 35 of a part of the invention; and Fig. 6 is a horizontal section of same on the dotted line 6 6 of Fig. 5.

In the drawings, 10 designates the bottle, which, except at the neck portion 11, will be 40 of any suitable form and construction. The neck portion 11 of the bottle will also be of any suitable or convenient construction, with the exception that it will be formed with the downwardly-converging sides 12 and the annular horizontal groove 13, the downwardly-converging sides 12 forming within the bottle-neck an inverted conical chamber 14.

Within the upper portion of the bottle-neck and immediately below the location for the 45 usual stopper or cork 15 is provided the plug

16, which is locked in position within the bottle-neck and comprises in its preferred form a solid piece of material having the annular groove 17 and series of oppositely-inclined grooves 18 19, said grooves 18 and 19 being 55 formed in the surface of the plug 16 and being out of alinement with one another, the grooves 19 leading upward from the lower edges of the plug into the annular groove 17 and the grooves 18 leading upward from the 60 annular groove 17 to the upper edges of the said plug 16. The outflow of the liquid from the bottle is through the grooves 19 into the annular groove 17, and thence through the grooves 18 to the point of discharge, said 65 grooves 18 and 19 forming outlet-passages for the liquid around the plug 16. The grooves 18 and 19 are oppositely inclined and out of alinement with one another, so as to prevent the introduction of an instrument downward 70 through said grooves into the lower portion of the bottle-neck.

The plug 16 may be secured within the bottle-neck in any convenient manner; but I have devised a special means for locking the plug 16 75 within the bottle-neck, and the said means comprise the spring 20, connected with said plug, and the annular groove 13, formed in the bottle-neck to receive the ends of said spring. The spring 20 is a flexible bar-spring 80 held at its middle portion within a vertically-disposed slot extending horizontally through an extension 21, projecting centrally downward from the plug 16. During the insertion of the plug 16 into the bottle-neck the 85 ends of the spring 20 will be wrapped or coiled about the extension 21, so that said spring may not interfere with the introduction of the plug 16 into the neck of the bottle. After the plug 16 has been pushed downward into the 90 bottle-neck until the spring 20 meets the annular groove 13 the ends of the said spring 20 will move outward into said groove 13 and operate as a bar to lock the plug 16 in position, said spring 20 at such time preventing any 95 further downward movement of the plug 16 and also preventing the withdrawal of said plug outward from the bottle-neck. The plug 16 after its insertion into the bottle-neck constitutes a stationary part, which will permit 100

the outflow of the liquid and also prevent the introduction of a wire or other means downward to the parts located below the annular groove 13.

- 5 Within the conical chamber 14, formed within the lower portion of the bottle-neck, is provided the valve or plug 22, which preferably will be in the form of a cork body or stopper 23, having upwardly-converging side 10 walls and encircled about its lower portion by a gasket 24, the upper edges of the gasket 24 being free of the said side walls and the lower edge of the gasket 24 being fastened or tightly bound against the lower side surfaces of the 15 said body 23. The gasket 24 may be of rubber and operates as a cup-piston, permitting the outflow of the liquid under proper conditions, but preventing the inflow of the liquid to the bottle. When the plug 22 is in its 20 lower position (shown in Figs. 1 and 2) and the bottle is in an upright position, said plug will seal the neck of the bottle and be maintained in such position by means of the weight 25, which is suspended from the plug 22 by 25 means of the rod 26, which extends downward through the plug 22 and through a free aperture in the weight 25, the lower end of the rod 26 being provided with a suitable head 27 to prevent the escape downward of the 30 weight 25 therefrom. The weight 25 is intended to be capable of a free sliding movement on the rod 26 during the tilting action of the bottle. The weight 25 is disposed within the bottle and below the neck portion thereof, 35 and upon the upper end of the weight 25 is provided a horizontal spider or frame 28, comprising, by preference, the crossed strips of whalebone or other flexible material 29, whose end portions project laterally beyond the 40 plane of the sides of the bottle-neck, so that they may contact with the shoulder portion 30 of the bottle below said neck when the bottle is inverted and the weight 25 slides on the rod 26 toward said neck.
- 45 It will be observed that a definite space is allowed between the upper end of the plug 22 when the latter is in its lower position and the lower end of the plug 16, and this space is left between the said parts so as to 50 allow the plug 22 when the bottle is inverted to move outward from its lower position and against said plug 16. When the bottle is tilted or inverted, the weight 25 will slide toward the bottle-neck on the rod 26 and the 55 plug 22 and rod 26 will move outward toward the plug 16, and when the plug 22 has thus left its lower position the liquid may flow around the gasket 24 of said plug 22 and thence around the plug 16 to the point of 60 discharge. When the weight 25 has moved toward the bottle-neck upon the rod 26, the liquid will press against the plug 22 and drive it outward toward and against the plug 16. When the plug 22 has attained its 65 outward position against the plug 16, a space will be created between the exterior walls of the gasket 24 and the inner surfaces of the

conical chamber 14 sufficient for the outflow of the liquid around the plug 22. When the bottle is again restored to its upright position, the weight 25 will slide downward on the rod 26 and operate to insure the return of the plug 22 to its lower sealing position. The frame 28, connected with the weight 25, prevents the contact of said weight with the 75 inner surfaces of the bottle and also maintains said weight and rod 26 in a substantially central position in line with the bottle-neck.

Any attempt to refill the bottle will be frustrated by means of the plug 22, since any pressure applied above the plug 22 will drive said plug to its lower position, in which it will seal the bottle-neck, and under such condition the gasket 24, arranged in the manner 85 described, will form a very effectual seal, since if it should be attempted to force the liquid into the bottle under pressure a portion of the liquid would find its way between the upper inner surfaces of the gasket 24 90 and the adjacent outer surfaces of the stopper or body 23 and cause the upper part of the gasket 24 to expand outward against the inner surfaces of the bottle-neck, thus creating broad contacting surfaces of the gasket 95 with the bottle-neck and effectually closing the latter.

The frame 28, composed of the flexible crossed strips 29, will be introduced downward through the bottle-neck, and this may 100 be accomplished since the said strips 29 are of flexible material and will expand outward after having passed downward below the lower end of the bottle-neck.

The present invention is not limited in 105 every instance to the special construction of plug 16 shown in Figs. 1 and 2 nor to the employment of the spring 20 as a means for locking said plug in position, since a very important part of the invention is located 110 below said plug 16.

In Figs. 5 and 6 I illustrate a modified form of the plug 16, this modification being illustrated to indicate that other means than the spring 20 may be employed for locking the 115 plug 16 in position. The plug shown in Figs. 5 and 6 is numbered 31 and corresponds, substantially, with the plug 16 shown in Figs. 1 and 2, with the exception that the plug 31 is provided with an annular groove 32, containing two semicircular pieces 33 33, which when closed together around and within the annular groove 32 have their outer edges within the vertical plane of the sides of said plug 31 and will not interfere with the introduction 120 of said plug into the neck of the bottle. After the plug 31 is within the bottle-neck and the bottle has been tilted or jarred to a slight extent the pieces 33 will ride outward from the annular groove 32, as shown in Figs. 5 and 130 6, and enter the annular groove within the bottle-neck, and thereby form the lock for preventing the withdrawal of the plug 31 from the neck of the bottle, said pieces 33 at

such time being partly within the annular groove 32 of the plug and partly within the annular groove formed in the bottle-neck.

What I claim as my invention, and desire 5 to secure by Letters Patent, is—

1. The bottle and the attachment therefor to prevent refilling, said attachment comprising an upper plug secured within the bottle-neck and having outflow-passages, and the 10 lower plug 22 disposed and movable within said neck below said upper plug and comprising the buoyant body portion 23 and the compressible gasket 24 encircling and carried by said body portion, said neck having the downwardly-converging side walls against which 15 said gasket may seal when said plug 22 is in its lower position, and said neck above the lower position for said plug 22 being enlarged to form a chamber through which the liquid 20 may flow around said plug 22; substantially as set forth.

2. The bottle having in its neck the annular groove and below said groove the downwardly-converging side walls forming the inverted conical chamber, and the attachment 25 to prevent refilling, said attachment comprising the upper plug having outflow-passages for the liquid and means to engage the walls of said groove for locking said plug in position, combined with the lower plug 22 disposed and movable within said chamber and comprising the buoyant body portion 23 and compressible gasket 24 encircling and carried by said body portion, said gasket when 30 the plug 22 is in its lower position being adapted to seat against the walls of said chamber; substantially as set forth.

3. The bottle having in its neck the downwardly-converging side walls forming the inverted conical chamber, and the attachment 40 to prevent refilling, said attachment comprising the upper plug having outflow-passages, and the lower plug 22 disposed and movable within said chamber and comprising the buoyant body portion 23 and the compressible gasket 24 encircling and carried by said body portion, said gasket being secured at its lower 45 edges in close contact with said body portion and thence flaring upwardly and outwardly

therefrom and being adapted when the plug 50 22 is in its lower position to seal against said walls; substantially as set forth.

4. The bottle having in its neck the annular groove and below said groove the downwardly-converging side walls forming the inverted conical chamber, and the attachment 55 for preventing refilling, said attachment comprising the upper plug having outflow-passages for the liquid and the transverse spring to move outward into said groove for locking 60 said plug in position, combined with the lower plug 22 disposed and movable within said chamber and comprising the buoyant body portion 23 and encircling compressible gasket 24, the latter when the plug 22 is in its lower 65 position, being adapted to seat against the walls of said chamber and when said plug is in its outer position, permitting the outflow of the liquid around the plug; substantially as set forth.

5. The bottle having in its neck the downwardly and inwardly converging walls forming the inverted conical chamber, and the attachment for preventing refilling, said attachment comprising an upper plug secured with 70 in the bottle-neck and having outflow-passages, the lower plug 22 movable within said chamber and comprising the buoyant body portion 23 and the compressible gasket 24 encircling and carried by said body portion and 75 adapted when the plug 22 is in its lower position to seal against said walls, the rod connected with said lower plug and extending downward therefrom the weight suspended within the body of the bottle by and free to 80 slide on said rod, and the horizontal open frame secured to and movable with said weight and adapted to move outward into contact with the upper portion of the body of the bottle when the latter is inverted; sub- 85 stantially as set forth.

Signed at New York, in the county of New York and State of New York, this 15th day of July, A. D. 1901.

FREDERIC A. MORLEY.
